 William Brooks

Application May 7, 1947, Serial No. 138,884

Term of patent 14 years

(Cl. D86—10)

To all whom it may concern:

Be it known that I, Walter S. Jackson, a citizen of the United States of America and a resident of Passaic, in the county of Passaic and State of New Jersey, have invented a new, original, and ornamental Design for a Cap for a Twin Lipstick, of which the following is a specification, reference being had to the accompanying drawing forming part thereof, in which—

Fig. 1 is a perspective view of a cap for a twin lipstick embodying my design.

Fig. 2 is a front elevation thereof.

Fig. 3 is a bottom view.

Fig. 4 is a longitudinal sectional view taken on the line 4—4 of Fig. 3.

I claim:

The ornamental design for a cap for a twin lipstick, as shown.

WALTER S. JACKSON.
